Inventor:

Peter M. Kling:
By Wright, Bent Atty's.

UNITED STATES PATENT OFFICE.

PETER M. KLING, OF ST. LOUIS, MISSOURI.

DESIGN FOR A TRUCK-FRAME.

SPECIFICATION forming part of Design No. 32,705, dated May 22, 1900.

Application filed March 30, 1900. Serial No. 10,851. Term of patent 14 years.

To all whom it may concern:

Be it known that I, PETER M. KLING, a citizen of the United States, residing at the city of St. Louis, in the State of Missouri, have invented and produced a new and original Design for a Truck-Frame, of which the following is a specification, reference being had to the accompanying drawings, forming a part thereof.

10 Figure I is a plan view of a truck-frame, showing my design. Fig. II is a side view.

As shown in the drawings, the leading or material feature of my design consists of side portions 1, having downwardly-extending bends 2 and double end portions 3, joined to the side portions by rounded corners 4. The side portions are connected together by bars

5, and extending across one end of the frame is a bar 6. Surmounting the side portions are inverted-U-shaped risers 7, having outturned 20 feet extending to cam-shaped projections. Between the risers are bracket-like portions 8, located entirely on the elevated parts of the side portions.

Having thus described my invention, the 25 following is what I claim as new therein and desire to secure by Letters Patent:

The design for a truck-frame, as herein shown and described.

PETER M. KLING.

In presence of—

E. S. KNIGHT,
M. P. SMITH.
